(57) **CLAIM**

The ornamental design for a hot air gun, as shown and described.

DESCRIPTION

FIG. 1 is a perspective view of a hot air gun showing our new design;

FIG. 2 is a front elevation view of the hot air gun of FIG. 1; FIG. 3 is a rear elevation view of the hot air gun of FIG. 1; FIG. 4 is a left-side elevation view of the hot air gun of FIG. 1;

FIG. 5 is a right-side elevation view of the hot air gun of FIG. 1;

FIG. 6 is a top plan view of the hot air gun of FIG. 1; and, FIG. 7 is a bottom plan view of the hot air gun of FIG. 1. The broken lines in the FIGURES depict portions of the hot air gun that form no part of the claimed design.
